APPLIQUÉ TYPE DOOR PANEL OR SIMILAR ARTICLE

James E. Thompson, Torrance, Calif., assignor to Palazzo
Panels, a corporation of California

Filed Aug. 5, 1965, Ser. No. 86,451

Term of patent 14 years

(Cl. D13—1)

FIG. 1

FIG. 2

FIG-3

FIG-4

FIGURE 1 is a plan view of an appliquéd type door panel or similar article showing my new design;

FIGURE 2 is a partially cross-sectional and partially end elevational view thereof taken, as indicated, along the lines 2-2 of FIGURE 1;

FIGURE 3 is a plan view of an appliquéd type door panel or similar article showing a modification of my new design thereof; and

FIGURE 4 is a plan view of an appliquéd type door panel or similar article showing another modification of my new design thereof.

I claim:

The ornamental design for an appliquéd type door panel or similar article, substantially as shown and described.
